[57] CLAIM

The ornamental design for a field and winter sports jacket, substantially as shown and described.

DESCRIPTION

FIG. 1 is a front perspective view of a field and winter sports jacket showing my new design;

FIG. 2 is a rear perspective view with the hood raised;

FIG. 3 is a fragmentary front, top and right side perspective view of the jacket with the hood raised;

FIG. 4 is a plan view of the inside of the jacket in the condition of FIG. 1;

FIG. 5 is a front elevational view with the hood concealed and the inside bottom corner of the front right flap folded over;

FIG. 6 is a fragmentary front and left side perspective view; and

FIG. 7 is a rear elevational view in the condition of FIG. 1.
